CLAIM

We claim the ornamental design for a raised motorcycle stand, as shown and described.

DESCRIPTION

FIG. 1 is a perspective view of a raised motorcycle stand;

FIG. 2 is a right side view of the raised motorcycle stand of FIG. 1;

FIG. 3 is a left side view of the raised motorcycle stand of FIG. 1;

FIG. 4 is a top view of the raised motorcycle stand of FIG. 1;

FIG. 5 is a front view of the raised motorcycle stand of FIG. 1;

FIG. 6 is a rear view of the raised motorcycle stand of FIG. 1; and,

FIG. 7 is a bottom view of the raised motorcycle stand of FIG. 1.

The portions shown in broken lines form no part of the claimed design.
